* cited by examiner

Primary Examiner — Holly Baynham*Assistant Examiner* — Rhea Shields(74) *Attorney, Agent, or Firm* — H. John Rizvi; Gold & Rizvi P.A.(57) **CLAIM**

I claim the ornamental design for a hexagonal power outlet hub, as shown and described.

DESCRIPTION

FIG. 1 is a front isometric view of my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.
In the drawings, the broken lines are for the purpose of illustrating environment only and form no part of the claimed design.
